AERIAL SHELL

Eugene Jeairis, Beaumont, Tex.

Application January 3, 1935, Serial No. 276

1 Claim. (Cl. 102—2)

This invention relates to an aerial bomb or shell, the general object of the invention being to provide means whereby a plurality of bullets are discharged from the device when the same 5 strikes the ground.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding 15 parts throughout the several views, and in which:

Fig. 1 is an elevation showing one form of the invention.

Fig. 2 is an elevation with parts broken away showing another form of the invention.

Fig. 3 is a top plan view of Fig. 1.

Fig. 4 is a vertical sectional view through the upper part of Fig. 1.

Fig. 5 is a transverse sectional view through the invention.

Fig. 6 is a vertical sectional view through the lower part of Fig. 1.

Fig. 7 is a fragmentary interior view of the inner cylinder showing how the recess for a trigger member is arranged therein.

Fig. 8 is a view of one of the trigger members.

Fig. 9 is a detail sectional view showing how the trigger member engages the cartridge, in the modified device of Fig. 2.

In these drawings, the body A of the device is composed of the inner cylinder 1 and the outer cylinder 2, each cylinder having a plurality of holes 3 in its side walls and short tubes 4 are located between the two cylinders with their ends suitably connected to said cylinders and the bores of the tubes are in alignment with the holes in the cylinders and form barrels for the cartridges 5. The inner end of each hole in the inner cylinder 1 is countersunk to receive the rim of the cartridge as shown. A third cylinder 6 is placed within the inner cylinder and is of greater thickness than the other cylinders and is formed with the substantially L-shaped openings 7 and the holes 8, there being one of these openings 7 and a hole 8 adjacent each cartridge. An angle-shaped trigger member 9 has its long limb fastened to a sloping wall of the opening 7 and the short limb carries a pin 10 which passes through the hole 8, the trigger member being of spring material and having a portion of its long limb 45 and a short limb extended into the cylinder 6.

Upper and lower cover plates 11 are suitably attached to the ends of the cylinders 1 and 2, and each cover plate has an opening therein of the same diameter as the interior diameter of the cylinder 1 and a hammer member 12 is slidably arranged in the cylinder 6, the hammer member having a cylindrical part and conical part with the stem 13 connected to said parts with one stem extending upwardly and the other downwardly and the upper end of the upper stem 10 carries the blades 14 which cause the device to drop in a vertical position.

In that form of the invention shown in Figs. 1, 4 and 6, the lower part of lower stem 13 carries a disk 15 which is adapted to strike the cup-shaped bottom member 16 on the lower end of the device when the device strikes the ground so that the hammer member will not penetrate the ground as it moves downwardly when the device strikes the ground and comes to a sudden 15 stop which causes the hammer member to move downwardly to the position shown in Fig. 4 and during this movement of the hammer member, it will move the trigger members outwardly and thus cause the pins 10 to explode the cartridges 20 and the bullets will pass from the side walls of 25 the device in all directions.

In that form of the device shown in Fig. 2, the lower stem 13 has a pointed end and carries a disk 15 so that when this disk strikes the ground, the hammer member will come to a sudden 30 stop while the body of the device continues to move downwardly and thus the hammer member 12 will explode the cartridges by means of the trigger members as the body moves downwardly and the hammer member is held stationary. In this form of the device, the trigger members are reversed as shown in Fig. 9.

The cylinder 6 can be removed through the top of the device but is held in place by the bolts 40 20 which pass through the inner and outer cylinders into holes formed in the cylinder 6 as shown in Fig. 4. As many of these bolts can be used as desired and they may be placed at each end of the device. Thus, by removing the bolts, 45 the cylinder 6 can be removed from the device to permit the cartridges to be placed in position and then the cylinder 6 is replaced and the bolts are replaced to hold the cylinder in position.

I also provide latch members 21 and 22 for preventing the hammer member from dropping out 50 of the device when it is being transported from place to place, the members 21 being pivoted to the cylinder 6 and the members 22 to the hammer member and these latch members are ar- 55

ranged as shown in Fig. 3 when the device is being transported from place to place. Just before the device is dropped, these latch members are swung to inoperative position.

5 I also firmly attach spring strips 23 to the hammer member and these strips overlap the cylinder 6, as shown in Fig. 3. When the device strikes the ground, these strips will bend and thus permit the hammer member to move downwardly 10 through the cylinder 6.

In order to prevent turning movement of the hammer member when the device is being transported or stored, I provide a small key 24 which engages the short keyway in the top part of the 15 hammer member 12, the key being fastened to the top of the cylinder 6 as shown in Fig. 3. Thus, as before stated, this key and keyway will prevent 20 rotary movement of the hammer member.

It will, of course, be understood that as many 25 of the latch members can be used as desired, as well as the strips 23. Also the barrels 4 and holes 3 can be arranged in the device as desired and need not be arranged in vertical rows as shown, the idea being to have the bullets pass from the 30 device in all directions, when the device strikes the ground after it is dropped from an aircraft so that the bullets will inflict the maximum amount of damage to the enemy troops. While Fig. 2 does not show the bladed upper end of the 35 stem, it is to be understood that this form of the device is also provided with this bladed stem.

It is thought from the foregoing description that the advantages and novel features of the invention will be readily apparent.

It is to be understood that changes may be made in the construction and in the combination 5 and arrangement of the several parts, provided that such changes fall within the scope of the appended claim.

I claim:

A device of the class described, comprising a 10 cylindrical body, radially arranged barrels carried by the body for receiving cartridges, a cylinder removably fitting in the body for holding the cartridges in the barrels, means for removably holding the cylinder in the body, firing means 15 carried by the cylinder for firing the cartridges, a hammer member slidably arranged in the cylinder for operating the firing means when the device strikes the ground, a casing at the lower end of the body and the hammer member having 20 a part at its lower end for engaging the bottom of the casing, whereby when said bottom of the casing strikes the ground, the hammer member will move downwardly until said part, at its lower end, strikes the bottom of the casing, when further 25 downward movement of the hammer member is stopped, a stem connected to the upper end of the hammer member and fins connected to the upper end of the stem.

EUGENE JEANIS. 30
